UNITED STATES PATENT OFFICE

2,567,218

PARTITIONED CIGARETTE CASE WITH
SPRING OPERATED CLOSURES

Edwin A. Lemire, Providence, R. I.

Application November 12, 1946, Serial No. 709,144

5 Claims. (Cl. 206—41)

1

The present invention relates to a container and it particularly relates to a cigarette container.

Although the container may be made of wood or die cast aluminum or magnesium, the invention will be described in its application to containers of molded, cast, or machined, transparent or opaque plastic and resinous materials.

It is among the objects of the present invention to provide a novel, attractive, light weight, compact, cigarette container with high capacity of molded plastic, which may be readily manufactured from inexpensive molds, which will have few parts and be readily assembled, and which may be used for long periods without breaking or malfunction.

Still further objects and advantages will appear in the more detailed description set forth below, it being understood, however, that this more detailed description is given by way of illustration and explanation only and not by way of limitation, since various changes may be made by those skilled in the art without departing from the scope and spirit of the present invention.

In accomplishing the above objects, it has been found most satisfactory to provide a base container or receiver with split swinging cover elements hingedly mounted on the sides thereof. The cover elements are moved apart to open the container or latched together to close the container by means of reciprocal partition members having resilient or spring actuating elements mounted in recesses therein.

In the drawings which show an embodiment of the invention by way of illustration and not by way of limitation,

Fig. 1 is a side perspective view of the cigarette container in closed position.

Fig. 2 is a vertical side sectional view taken upon the line 2—2 of Fig. 1.

Fig. 3 is a side perspective view similar to Fig. 1, showing the cigarette container in opened position.

Fig. 4 is a vertical side sectional view taken upon the line 4—4 of Fig. 3, and

Fig. 5 is a fragmentary end perspective of the cover elements of the container illustrating how the end cigarettes are cammed back into the case.

In Figs. 1 to 4, the container base A, with the swinging closure members B, B are shown of rectangular shape, but they may be of other shapes. They are preferably molded of a synthetic or natural plastic or resinous material of transparent, translucent or opaque nature. The container elements A and B may also less desirably be made of metal or wood.

The central reciprocating partition structure C in conjunction with the springs D and E serves to lock the closures B, B in the closed position of Fig. 2 or to swing them into the open position of Fig. 4 when the lock is released.

2

As shown, the container has the bottom wall 10, the side walls 11 and the end walls 12. The cover elements B have the side walls 13, the end walls 14 and the top walls 15.

The top walls 15 interiorly are provided with notches or recesses 16 which form the locking teeth 17. The teeth 17 engage the notch 18 in the upper end of the reciprocating wall C.

The swinging elements B have hinge extensions or lugs 19 which fit into the recesses 20 in the top edges of the walls 11. The hinge pins 21 are inserted from the sides as indicated best in Fig. 1.

The wall C slides in a groove or channel 22 in one of the walls 11 of the container A and it also has an extension 23 at the opposite side thereof projecting through and beyond a slot 24 in the wall 11. The edge of the extension 23 is serrated or transversely grooved at 25 to afford a finger actuating portion.

The wall C has a bottom recess 26 receiving a coil spring D which reacts against the bottom wall 10 of the container A. The sides of the wall are recessed at 28 to receive the bent wire springs E. These springs E have inturned bottom legs 29 fitting into recesses 30. The vertical legs of the springs E will reciprocate in the recesses 28. The springs E are biased outwardly against the walls 11 when in released position as shown in Fig. 4.

The upper ends of the legs have outwardly directed portions 33 with turned in ends 32 which press against the interiors of the side walls 13 of cover elements B of the cigarette case A when it is in closed position, as shown in Fig. 2, and which extend out over the lower side walls 13 as shown in Fig. 4 when in opened position.

In assembly, the container element A, the cover elements B and the wall element C are desirably all molded of a Vinylite, acrylic, styrene, amino-

plast or cellulosic resinous or plastic material of opaque or transparent character. The lugs 19 and recesses 16, 18, 20 and 28 are preferably molded into the elements A, B and C. The recess 26 may then be drilled. The holes for the pivot pins 21 and the holes for the inturned ends 29 of the springs E may also be drilled.

In assembly of the partition D, the spring D is inserted in the recess 26 and the partition C is inserted in the slot 22. The partition C has an enlargement or extension 60 (see Figs. 2 and 3) below the recesses 28 which is received in said slot 22. There is sufficient play or looseness to enable the portion 25 to be pressed downwardly inside of the wall 11 until it snaps into the slot 24.

The cover elements B may then be assembled in the casing A by the pins 21. The partition C with springs E and D in position may then be assembled with casing A.

In operation, pressing down on the element 25

when the container A is closed as shown in Figs. 1 and 2, will release teeth 17 from notch 18. The ends 32 of the springs D will then throw the cover elements B outwardly and downwardly to the position of Figs. 3 and 4.

The cigarettes, ten or twenty in number, which are stacked vertically in the casing A, end up, may then be most readily removed.

In closing the container A, the cover elements B are pressed back, and when the teeth 17 strike the top of the partition C, they will press it downwardly against the spring D, until the teeth engage the notch 18. Then the spring 18 will move the partition C up to position of Fig. 2 locking the container sections B in position.

When only a small number of cigarettes are in the container they tend to fall to the side as indicated at 52 in Fig. 5 and to be clamped between the edges of the side walls 14 of the cover elements 15. The camming edges 51 will then contact the cigarette 52 and move it back into the container before the walls 14 contact.

The container is inexpensive, attractive, of light weight and readily handled by man or woman.

As many changes could be made in the above container and many apparently widely different embodiments of this invention could be made without departing from the scope of the claims, it is intended that all matter contained in the above description or shown in the accompanying drawings shall be interpreted as illustrative and not in a limiting sense.

What is claimed is:

1. A cigarette case having a flat deep rectangular receiver for holding two layers of cigarettes in vertical side by side position, a reciprocable vertical partition fitted into said receiver, said receiver having a vertical groove in one interior wall thereof to receive and guide one vertical edge of the partition and a vertical slot in the other wall thereof to receive a ridged finger-engaging extension projecting outwardly from the other vertical edge of the partition and split cover elements of rectangular shape hingedly mounted on the side walls of said receiver, said cover elements having teeth adjacent the inside edges thereof and said partition having a notch at its upper edge to engage said teeth and latch said cover elements together in closed position, said partition having a coil spring at its bottom edge to react against the bottom of the receiver and bias the partition upwardly and wire springs received in recesses in its side edges to press said cover elements outwardly and downwardly.

2. A cigarette casing comprising a relatively deep rectangular holder to carry two parallel rows of cigarettes uprightly, a central reciprocatory vertical partition positioned so that the plane will extend transversely to the long horizontal dimension of the holder, two angular lid members pivotally mounted on the longer edges of said holder, said casing having a vertical groove at one side to receive said partition and having a slot at the other side, said partition having an actuator member projecting through said slot and said vertical partition having side recesses carrying spring members to bias said lid members outwardly as the partition rises and having a bottom recess to receive a coil spring to bias said partition upwardly.

3. A cigarette casing comprising a relatively deep rectangular holder to carry two parallel

rows of cigarettes uprightly, a central reciprocatory vertical partition positioned so that the plane will extend transversely to the long horizontal dimension of the holder, two angular lid members pivotally mounted on the longer edges of said holder, the inside side edges of said lid members being beveled to cam the cigarettes inwardly, said casing having a vertical groove at one side to receive said partition and having a slot at the other side, said partition having an actuator member projecting through said slot and said vertical partition having side recesses carrying spring members to bias said lid members outwardly as the partition rises and having a bottom recess to receive a coil spring to bias said partition upwardly.

4. A cigarette casing comprising a relatively deep rectangular holder to carry two parallel rows of cigarettes uprightly, a central reciprocatory vertical partition positioned so that the plane will extend transversely to the long horizontal dimension of the holder, two angular lid members pivotally mounted on the longer edges of said holder, said lid members and said partition having interengaging notches and teeth to latch the lid members in closed position, said casing having a vertical groove at one side to receive said partition and having a slot at the other side, said partition having an actuator member projecting through said slot and said vertical partition having side recesses carrying spring members to bias said lid members outwardly as the partition rises and having a bottom recess to receive a coil spring to bias said partition upwardly.

5. A cigarette casing comprising a relatively deep rectangular holder to carry two parallel rows of cigarettes uprightly, a central reciprocatory vertical partition positioned so that the plane will extend transversely to the long horizontal dimension of the holder, two angular lid members pivotally mounted on the longer edges of said holder, said casing having a vertical groove at one side to receive said partition and having a slot at the other side, said partition having an actuator member projecting through said slot and said vertical partition having side recesses carrying spring members to bias said lid members outwardly as the partition rises and having a bottom recess to receive a coil spring to bias said partition upwardly.
